UNITED STATES PATENT OFFICE.

ALFRED SWANSON, OF BILLINGS, MONTANA.

LIFTING JACK.

Application filed January 29, 1923. Serial No. 615,675.

To all whom it may concern:

Be it known that I, ALFRED SWANSON, a citizen of the United States of America, residing at Billings, in the county of 5 Yellowstone and State of Montana, have invented certain new and useful Improvements in Lifting Jacks, of which the following is a specification.

My invention relates to new and useful 10 improvements in lifting jacks, and more especially to a lifting jack which is relatively small in size, and used principally for lifting automobiles, trucks or other devices of similar size or weight.

One of the principal objects of the invention is to provide a lifting jack, relatively small in size, compact in form; quickly and easily operated, and capable 15 of sustaining a relatively heavy load.

Still another object of the invention is to provide a lifting jack which may be quickly and easily operated to lift the object desired, and after being so operated, a frictional member may be brought into action 20 to thereby further retain the object in its lifted position and thus relieve the main pawl or catch of the load.

Still another object of the invention is to provide a lifting jack which may be readily 25 operated to lift the load, after which the frictional element is brought into contact with the elevating post or stem of the jack to retain the load. When it is desired to lower the load, the main catch will be first released, then the frictional element slightly 30 released and the load will then descend slowly or rapidly as desired, depending upon the amount of release movement applied to the frictional element.

Still another object of the invention is to provide a lifting jack, which is relatively 35 simple in construction; compact in nature; capable of sustaining a relatively heavy load; quickly and easily operated to a raised 40 position, and more easily lowered to its normal position.

With these and other objects in view, the invention consists in certain new and novel structures, and combination of parts as will 45 be hereinafter described and pointed out in the claims.

Referring now to the drawings showing a preferred embodiment of the invention,

Fig. 1 is a side elevation of my improved 50 jack showing a portion of the casing removed for the sake of clearness, the lifting

post being shown in a partly elevated position.

Fig. 2 is a front elevation showing the 60 post in a partly elevated position.

Fig. 3 is a vertical sectional view taken on line 3—3 of Fig. 1 looking in the direction of the arrows.

Fig. 4 is also a vertical central sectional 65 view taken on line 4—4 of Fig. 2.

Fig. 5 is also a vertical sectional view similar to Fig. 3, but looking in the opposite direction of the arrows; the lifting pawls being shown in their engaged position.

Fig. 6 is a transverse sectional view taken 70 on line 6—6 of Fig. 1 looking in the direction of the arrows, and

Fig. 7 is a similar view taken on line 7—7 of Fig. 1.

Referring now more in detail to the drawings there is shown a lifting jack comprising a base 1, on which there is formed an integral hollow standard 2, preferably rectangular in cross-section, and open at its 80 top 3. Two side plates 4 in the form of casings are shown which are tapered at their upper ends as at 5, these casings being secured to the standard and base as at 6 by screws or other similar means. On the front face of the standard are the projecting wings 7, as may be clearly seen in Fig. 2, these wings fitting within cut out portions 8 formed in the side plates 4. These wings 7 also extend inwardly as at 9 and shown in Fig. 1 and form a guide for a part of the lifting mechanism which will be hereinafter more fully explained. Further cut out portions 10 are shown in the front faces of the side plates 4 through which pass the 85 portions of cams 11 which are in turn mounted on the ends of the main shaft 12, this shaft turning in the bearings 13 secured on the face of the standard 2; the shaft being operated by a lever 15 which fits within a socket 16 formed on the shaft 12.

As may be seen in Fig. 4 an aperture 17 is formed in the standard near the upper end thereof which aperture is surrounded by the boss 18 to which, in turn, is fastened the small housing 19 in which is the spring 20, while passing through the housing and through the aperture is the main retaining pawl 21 which is threaded at its rear end as at 22 and on which there is loosely threaded the wheel 23. The spring 20 will normally force the pawl 21 inwardly as 90 95 100 105 110

shown in Fig. 4, but it may be withdrawn by a turning of the wheel 23 in a clockwise direction.

A further aperture 24 is formed in the rear of the standard as may be clearly seen in Fig. 4 about which is the boss 25, to which is secured the internally threaded housing 26 to receive the post of the externally threaded frictional member 27. The post 10 has the groove 28 formed on its inner end, and a frictional block 29 is locked by the set screw 30 thereto. This frictional block 29 slidably fits within the aperture 24 and is provided with the small cut out portion 15 31 on its rear, for the reception of the inner end of the post as before mentioned. On the outer end of the frictional member is the small wheel 32 so that the frictional block 29 on it may be withdrawn from 20 within the hollow casing or may be advanced therein for contact with a plane face of the lifting post 33, now to be described.

This lifting post is also rectangular in cross-section, slidably fits within the hollow standard 2, and has the head 34 which may be integral therewith, or may be fastened to the same. On the two faces of this post 33 are formed angular detents 35 while on the front face of the post are formed 30 similar detents 36, the detents in both instances, not quite extending across the entire faces of the post, but in alignment.

The detents 36 formed on the front face of the post receive the aforementioned main 35 retaining pawl 21 as the post is elevated in its step by step movement.

Now, for elevating this post in its step by step movement, there are shown two guide members 37 with the lifting pawls 40 secured thereto, one being mounted on each side of the standard 2 and as they are similar, a description of one will suffice. Each guide member 37 is provided with what I term a short leg 38 and a long leg 39, the 45 short leg 38 being cammed by the cam 11 on the movement of the handle 15. To the top of the guide member is secured the pawl 40 as may be clearly seen in Figs. 3 and 5, the nose of the pawl 41 extending inwardly in a 50 plane beyond that of its stem.

Referring again for the movement to the standard 2, there will be noted at the opposite sides thereof and near its top the openings 42, having the lower tapered walls 43, the taper of these being substantially that of the incline of the inner sliding faces of the pawl 40. The pawl 40 is also hingedly attached to the upper end of the guide member 37 and as it is spring-pressed, its tendency is to normally extend inwardly so that when the guide member 37 is first raised, the inner face of the pawl will slide upwardly and inwardly on the tapered surface 43 of the opening 42, the nose thereof 60 engaging the detents 35 formed in the sides

of the post and then continue in a vertical or upright path of movement.

As before mentioned, there are two guide members 37 and two pawls 40 attached thereto, so that the post is lifted simultaneously from its opposite sides when the lever 15 is operated. For each guide element also, there is an upper bearing 44 which encircles the upper portion of the long leg 39, which leg is rectangular in cross-section at this point. The lower end 45 of the long leg 39 is rounded and passes through a bearing 46 against which abuts the spring 47, its lower end abutting against a collar 48 on the leg, which collar may be held in place by the pin 49. The purpose of this spring is to return the guide element and its pawl to its normal position after the guide element has been raised and the handle then elevated by the operator. As will be remembered, there is formed on the face of the standard the wings 7 and they, in turn, have the inwardly extending flanges 8 which form bearings for the guide members 37 during their upward and downward movement.

As far as the specification has proceeded, it will be seen that on the operation of the handle 15 in a downward direction, the cams 11 on the opposite sides of the standard will contact with the short legs 38 of the guide members 37 and as these guide members are raised, the pawls 40 being spring-pressed, will slide upwardly along the tapered wall 43 and inwardly through the openings 42, and engage the detents 36 on the side of the post and raise the same. As the post is raised each step, the main retaining pawl 21 will be forced outwardly as the pawl rides along the surface of the detents and will then spring inwardly and retain the post while the handle is being moved upwardly while the guide members are retracted by the springs 47 and the pawls 40 slide downwardly and outwardly over the tapered walls 43.

Now, to remove the weight from the main retaining pawl 21 and to further sustain the load which falls on the lifting post, after the post has been raised to its desired position, the frictional member 27 will be screwed inwardly so that the frictional block 29 will engage the plane surface 51 on the rear of the post. This rear surface 51 is also slightly tapered from a portion near its top to its lower end as may be clearly seen in Fig. 4, the purpose of this being that if the frictional member is loosened slightly, the weight of the load on the post will not force the same down too rapidly as a binding action will take place between the frictional block and the tapered surface formed on the rear of the post.

To permit this post to drop either slowly or rapidly, it will, of course, first be neces-

sary to turn the wheel 23 to thus retract the main retaining pawl 21.

From the foregoing, it will be seen that the operation of the jack is exceedingly simple, the movement of the handle in a downward direction causing the pawls at the sides to move upwardly and inwardly and raise the post in a step by step movement, the main retaining pawl holding the post while the handle is then raised. After the raising post has elevated the load to its desired position, the frictional member may be operated to tightly hold the post in this desired position.

When it is desired to lower the load and the post, the main retaining pawl 21 may be retracted by a movement of the wheel in a clockwise direction after which the wheel 32 of the frictional member 27 may be turned slightly and the post may be lowered slowly or rapidly depending on the amount of release applied to the frictional member.

It will also be seen that the jack is one that may be elevated or lowered rapidly and by providing the frictional member as shown, any or all of the strain will be taken from the main retaining pawl and transferred to the frictional member and the side of the post. In this way, a jack is provided which will stand greater loads than the jacks of the same relative size which are not formed with the independent frictional locking means.

The jack is also one which is neat in appearance of great strength and relatively cheap to manufacture.

Many slight changes might be made without in any way departing from the spirit and scope of the invention.

Having thus described the same, what I claim as new and desire to secure by Letters Patent is:—

1. A lifting jack comprising a base, a standard on said base, a lifting post in said standard, means cooperable with two faces of said lifting post for elevating the same, a main pawl for engaging another face to retain the lifting post as it is operated step by step, and an independent auxiliary member for engaging the fourth face of the lifting post.

2. A lifting jack comprising a base, a standard on said base, a lifting post rectangular in cross-section, means cooperable with two of the faces for elevating the lifting post step by step, a spring-pressed pawl for engaging a third face of the post to retain the post as the same is being elevated, and a frictional member to be independently operated to engage the fourth face of said post to retain the post in a desired position.

3. A lifting jack comprising a base, a standard on said base, and a post rectangu-

lar in cross-section movable within said standard, lifting pawls located on the sides of said standard cooperating with the sides of said lifting posts for elevating said post, means cooperable with said lifting pawls to operate the same, a spring-pressed main pawl for retaining the elevating post and a threaded movable frictional element for engaging the rear face of said post to retain the lifting post at any desired point in its elevation.

4. A lifting jack comprising a base, a standard, a lifting post movable in said standard, elevating means cooperating with said standard to raise the same step by step, means for retaining the lifting post in its step by step movement, frictional means for engaging said post independent of the lifting and retaining means, said first mentioned retaining means capable of being released so that when said frictional retaining means is released, the lifting post may descend rapidly.

5. A lifting jack comprising a base, a standard on said base, a lifting post movable in said standard and provided with detents on three of its faces and its fourth face being tapered, lifting pawls located on the sides of said standard and cooperating with the detents on the two side faces of the lifting post, means for operating said lifting pawls to elevate said lifting post step by step, a retaining pawl for engaging the detents on the front face of said post, an independent frictional element for engaging, when operated, the tapered fourth face of said post, so that the lifting post may be held in a desired position and so that after the main retaining pawl has been released, the frictional element may be slightly released and its engagement with the tapered portion of the post permit the lifting post to descend slowly.

6. A lifting jack comprising a base, a standard on said base, a lifting post movable in said standard, detents formed on three of the faces of said lifting post and the fourth face being tapered substantially throughout its length, elevating means secured to said standard and cooperating with two faces of the lifting post to raise the same step by step, a retaining pawl engaging the detents in the third face of said lifting post, means for positively withdrawing the pawl from engagement with said detent, independent operable frictional means mounted in said standard for engaging said tapered face of said post to retain the post in desired position, and means for slowly releasing said frictional means so that when said retaining pawl is withdrawn, said frictional means may be operated to lower the lifting post as slowly or rapidly as desired.

7. A lifting jack comprising a base, a standard mounted thereon, a lifting post

movable in said standard and having detents formed on three faces thereof, means mounted on the standard and projecting therethrough when operated for cooperation with the detents on two of the faces to elevate said lifting post, a spring-pressed pawl also passing through said standard and cooperating with detents on the third face for retaining the post in its step by step movement, means for releasing said spring-pressed pawl from cooperation with said detents, an independent frictional means for engaging the fourth face of said post also extending through said standard, and means for releasing the same so that the lifting post may be dropped quickly after the main retaining pawl has been operated.

8. A lifting jack comprising a base, a hollow standard mounted on said base, a lifting post in said standard, said standard being provided with openings in its side portions and said openings provided with tapered lower walls, lifting pawls mounted on the outer side of said standard to cooperate with said posts, means for operating said pawls, automatic means for forcing said pawls inwardly through the openings in said post as they pass along the tapered walls and a retaining pawl for holding said post in its step by step upward movement.

9. A lifting jack comprising a base, a hollow standard mounted on said base, a lifting post provided with detents in said standard, said standard being provided with openings in its sides, said openings provided with tapered lower walls, lifting pawls slidably mounted on the outside of said standard to cooperate with said detents, means for elevating said pawl and spring means forcing said pawls inwardly through the openings in said post as they pass upwardly along the tapered walls, a retaining pawl for holding said post in its step by step upward movement and independent frictional means for engaging said post to retain the post in any desired position.

10. A lifting jack comprising a base, a hollow standard mounted on said base, a lifting post in said standard provided with detents therein, said standard being provided with openings in its sides, said openings provided with tapered lower walls, guide members slidably mounted on the outer sides of said standard, spring-pressed pawls secured to said guiding members, means for elevating said guiding members, said spring-pressed pawls passing through the openings in said standard as they slide along the lower tapered walls of said opening and engaging detents in said posts to elevate the same, and a retaining pawl engaging other detents in said posts for holding said post in its step by step movement.

65 11. A lifting jack comprising a base, a

hollow standard mounted on said base, a lifting post in said standard provided with detents on a plurality of its faces, said standard being provided with openings in its sides, said openings provided with tapered lower walls, guide members slidably mounted on the outer sides of said standard, said guide members each provided with a short leg and a long leg, spring-pressed pawls secured to the upper ends of said guide members for cooperation with said post, means operable with the short legs of said guide members for elevating the same, said spring-pressed pawls passing through the openings in said standard as they slide upwardly along the lower tapered walls thereof and engaging detents in said post to elevate the same, and a retaining pawl engaging other detents in said post for holding said post during its step by step movement.

12. A lifting jack comprising a base, a hollow standard on said base, a lifting post in said standard provided with detents on a plurality of its faces, said standard provided with openings in its sides, said openings provided with tapered lower walls, guide members slidably mounted on the outer sides of said standard and, each of said guide members provided with a short and long leg, spring-pressed pawls secured to the upper ends of said guide members for cooperation with the detents in said post, means operably contacting with the short legs of the guide members for elevating the same, and means connected with the guide members for returning the same to their normal position, said spring pressed pawls passing through the openings in said standard, as they move upwardly along the lowered tapered walls thereof, and engaging the detents in said post to thereby elevate the same when said guide members are operated and a retaining pawl retaining detents in said post for holding said post in its step by step movement.

13. A lifting jack comprising a base, a hollow standard mounted on said base, a lifting post in said standard provided with detents on a plurality of its faces, said standard being provided with openings in its sides, said openings provided with tapered lower walls, guide members slidably mounted on the outer sides of said standard, said guide members each provided with a short leg and a long leg, spring-pressed pawls secured to the upper ends of said guide members for cooperation with said post, means operable with the short leg of said guide members for elevating the same, said spring-pressed pawls passing through the openings in said standard as they slide upwardly along the lower tapered walls thereof and engaging detents in said post to elevate the same, a retaining pawl engaging other detents in said post for holding said

post during its step by step movement, and independent frictional means for engaging a face of said post so that the same may be locked at a desired height.

5 14. A lifting jack comprising a base, a hollow standard mounted on said base, a lifting post in said standard provided with detents therein, an opening formed in said standard having a tapered lower wall, a 10 guide member mounted on the side of said standard having a pawl mounted at the upper end thereof, the same being spring-pressed and adapted to slide inwardly within said opening as its rides over the tapered 15 wall to engage the detents in said post, means for raising said sliding element and pawl upwardly within said opening to thereby elevate the post, a retaining pawl for engaging other detents in said post, means for 20 retracting said last mentioned pawl, independent locking means in the form of a frictional element for engaging a face of said post, and means for withdrawing said frictional element from contacting with 25 said post to thereby lower the same.

15. A lifting jack comprising a base, a hollow standard mounted on said base, a lifting post in said standard provided with detents in three of its faces, the fourth face 30 presenting a plane surface, two guide members slidingly mounted on the opposite sides

of said standard, each of said guide members being provided with a short and long leg, a cam mounted on said standard for engaging the said short legs to thereby elevate said guide members, bearings formed on said standard for guiding the long legs of each guide member, a further bearing located opposite the short legs for retaining the same in their sliding position when said 35 guide members are elevated; means connected to the long legs of each guide members for returning the guide members to their normal position, each of said guide members provided with an inwardly moving pawl, said standard provided in its sides and near its upper ends with openings, the lower walls of said openings being tapered so that as said pawls raise and lower, they 40 will move inwardly and outwardly into and 45 out of cooperation with said lifting post, a retaining pawl for holding the post in its step by step upward movement, and means for positively withdrawing the same, said standard also provided with a further 50 opening and an independently operated 55 frictional element movable therein for engaging the plane surface of said lifting post to thereby lock the lifting post in a desired 60 position.

In testimony whereof I affix my signature.
ALFRED SWANSON.
